UNITED STATES PATENT OFFICE.

EERKO SAMUEL AEILTS, OF LITTLE ROCK, IOWA.

APPLICATOR.

Application filed March 7, 1927. Serial No. 173,575.

My invention relates to improvements in applicators which are adapted for the application of medicine, and it consists in the combinations, constructions, and arrangements herein described and claimed.

An object of my invention is to provide an applicator by means of which a medicine may be deposited within the vagina adjacent the uterus.

10 A further object of my invention is to provide a device of the type described which may be readily inserted in the vagina and have its inner extremity positioned adjacent the os uteri and which is of a sufficient size 15 to prevent any backflow of the medicine that is deposited.

A further object of my invention is to provide a device of the type described which contains enough medicine for several applications.

20 A further object of my invention is to provide a device of the type described which may be readily applied in either a sitting, standing, or lying position.

25 A further object of my invention is to provide a device of the type described which will deliver, without waste, a predetermined amount of the medicine to the desired location.

30 A further object of my invention is to provide a device of the type described which is compact in form and due to this fact it may be conveniently carried while traveling and if desired it may be used in small inconvenient places, such as washrooms on trains.

35 Other objects and advantages will appear in the following specification, and the novel features of the invention will be particularly pointed out in the appended claims.

40 My invention is illustrated in the accompanying drawings, forming a part of this application, in which:

Figure 1 is a vertical section through one form of my invention, as applied to the uterus.

45 Figure 2 is an end elevation of the form shown in Figure 1.

Figure 3 is a vertical section through another form of my invention, and

50 Figure 4 is a fragmentary elevation of the form shown in Figure 3.

In carrying out my invention I provide a cylinder or barrel 1 having a threaded end 2 and a threaded end 3, see Figure 1. A cap 4 having a concave end 5 and a centrally disposed threaded opening 6 is provided

with an internally threaded portion 7 which is adapted to receive the threaded end 2. The cap 4 is provided with a tapering wall 8 and arcuate shaped grooves 9 which extend 60 from the tapering wall 8 to the opening 6. A plug 10 is provided with a threaded shank 11 which is receivable in the opening 6 when the device is not in use or when the cylinder 1 is being filled with a medicine indicated at 65 12.

After the desired amount of medicine has been disposed in the cylinder, a floating piston 13 is slidably disposed therein. The piston 13 provided with concave surfaces 14 and 70 15. A piston pump which is composed of a piston head 16 and a valve 17 is disposed in the cylinder 1. The piston head 16 is provided with concave surfaces 18 and 19, and a centrally disposed opening 20. The valve 75 17 is disposed in engagement with the piston head 16 and is adapted to close the opening 20. A cross-shaped stop member 21 is secured to the valve for a purpose hereinafter described. A rod 22 extends through an 80 opening 23 in a top 24 and has its ends rigidly secured to the valve head 16 and a thumb screw 25. The thumb screw 25 is provided with a threaded shank 26 which is adapted to be received in the opening 23. 85 The top 24 is provided with an internally threaded portion 27 for receiving the threaded end 3 of the cylinder 1.

From the foregoing description of the various parts of the device, the operation thereof may be readily understood. Let us assume that the cylinder 1 is approximately filled with the medicine 12, that the plug 10 is disposed in the opening 6 and that the threaded shank 26 is disposed in the opening 23. 90 This is the position of the device when it is not in use. In using the device, however, the plug 10 is removed, then by removing the thumb screw 25 from the top 24 the piston pump may be moved outwardly until the piston head 16 is in engagement with the top 24. During this movement of the piston valve the valve 17 is moved away from the opening 20 thus permitting air to pass through this opening, 100 around the prongs of the cross-shaped member 21, and into the cylinder. The device is now ready to be inserted into the vagina through the external orifice until the cap is in contact with the os uteri or mouth of the womb, see Figure 1. When this position has been reached, by forcing inwardly upon the 105

thumb screw 25, an air pocket is formed between the piston head 18 and the piston 15, due to the closing of the valve 17, and the floating piston 13 is moved inwardly. The inward movement of the floating piston causes a portion of the medicine to pass outwardly through the opening 6 and in engagement with the os uteri. A portion of the medicine passing from the opening 6 will pass through the grooves 9 and be distributed over the os uteri.

Each movement of the piston valve moves the floating piston inwardly, thus increasing the air-pocket and decreasing the amount of medicine. If one movement of the valve does not extract enough medicine the piston valve may be drawn outwardly again and then again forced inwardly.

In Figures 3 and 4 I have shown a modified form of my device which is composed of a cylinder 30 with a somewhat pointed arcuate shaped end 31.

The end 31 is provided with grooves 32 which extend from spaced-aparts adjacent the outer extremity thereof to an opening 33. A cover 34 having a central threaded opening 35 is disposed upon the opened end of the cylinder 30. A medicine 36 may be disposed in the cylinder 30. A piston 37 having a central threaded opening is then disposed in the cylinder 30. A threaded rod 38 extends through the opening in the piston 37 and is provided with a thumb screw 39 having a threaded shank 40, which is receivable in the opening 35 of a top 34.

In Figure 5 I have a diagrammatic view of the cylinder 30 and the manner in which the end 31 conforms to the os uteri when placed within the vagina. By unscrewing the rod 38 a desired distance the piston 37 may be forced inwardly thus forcing a portion of the medicine 36 through the opening 33 and distributed over the os uteri through the grooves 32.

When the form shown in Figures 3, 4, and 5 is not in use the rod 38 is forced inwardly until the disc 41 engages with the opening 33 and the threaded shank is received in the threaded opening 35.

50 I claim:

1. A device of the type described comprising a body portion for containing a medicine and adapted to be disposed in a vagina, an end for said body portion adapted to be disposed adjacent the mouth of the uterus and to conform to the outer wall thereof, means for discharging a desired quantity of the medicine from said body portion, said end having transversely extending grooves

therein for distributing a portion of the discharged medicine over the walls of the uterus.

2. A device of the type described comprising a body portion for containing a medicine and adapted to be disposed in a vagina, an end for said body portion adapted to be disposed adjacent the mouth of the uterus and to conform to the outer wall thereof, a floating piston disposed in said body portion adjacent the medicine, a piston valve disposed in said body portion, said piston valve comprising a piston head having an opening therethrough, a valve for closing said opening, means carried by said valve for manually moving said piston head outwardly, for allowing air to enter said body portion between said piston head and said floating piston, said valve being adapted to close said opening when said piston head is moved inwardly for forming an air pocket between said piston head and said floating piston, whereby an inward movement of said piston valve forces a portion of the medicine from said body portion and in contact with the mouth of the uterus.

3. A device of the type described comprising a body portion adapted to hold a medicine and having an outlet opening therein, a piston disposed in said body portion, a rod extending through said piston, whereby said piston may be moved for forcing a predetermined amount of the medicine through said opening, said rod being adapted to be moved with respect to said piston for varying the amount of the medicine which may be forced through said opening, and means carried by said rod for closing said outlet opening after the predetermined amount of medicine has been forced therethrough.

4. A device of the type described comprising a body portion adapted to hold a medicine and having an outlet opening therein, a piston disposed in said body portion, a rod extending through said piston, whereby said piston may be moved for forcing a predetermined amount of the medicine through said opening, said rod being adapted to be moved with respect to said piston for varying the amount of the medicine which may be forced through said opening, means carried by said rod for closing said outlet opening after the predetermined amount of medicine has been forced therethrough, and means for locking said rod and said piston against movement when said outlet opening is closed.

EERKO SAMUEL AEILTS.
